UNITED STATES PATENT OFFICE

OTTO MERKEL, OF PHILADELPHIA, PENNSYLVANIA

DESIGN FOR A ZITHER MANDOLIN

Application filed December 1, 1928. Serial No. 29,084. Term of patent 7 years.

To all whom it may concern:

Be it known that I, OTTO MERKEL, a citizen of the United States, residing at Philadelphia, in the county of Philadelphia and State of Pennsylvania, have invented a new, original, and ornamental Design for Zither Mandolin, of which the following is a specification, reference being had to the accompanying drawing, forming part thereof.

I claim:

The ornamental design for a zither-mandolin, as shown.

OTTO MERKEL,
